UNITED STATES PATENT OFFICE.

RUDOLPH COOPERSMITH, OF TORONTO, ONTARIO, CANADA.

WOVEN-WIRE MATTRESS.

1,253,469.

Specification of Letters Patent. Patented Jan. 15, 1918.

Application filed December 29, 1916. Serial No. 139,629.

To all whom it may concern:

Be it known that I, RUDOLPH COOPERSMITH, of the city of Toronto, in the county of York, in the Province of Ontario, Canada, have invented certain new and useful Improvements in Woven-Wire Mattresses, of which the following is the specification.

My invention relates to improvements in woven wire mattresses and the object of the invention is to devise in that class of mattress, in which a pair of independent woven wire sections are supported in the mattress frame, simple means for connecting these sections together so that they operate independently one of the other and prevent the sagging of the mattress in the center of the bed and it consists essentially of a mattress frame, a pair of woven wire mattress sections secured thereto in the usual manner, longitudinal metal strips extending parallel with the edges of the sections and having a series of perforations suitably spaced apart and formed in the edge of the strip, helical springs connecting the ends of the metal strip to the mattress frame and means passing through the perforations and co-acting with woven wire extending from the mattress section edge whereby the mattress section is connected to the metal strip as hereinafter more particularly explained by the following specification.

The figure represents a plan view of the central portion of a mattress and frame showing the opposing portions of the mattress section, the longitudinal metal strip interposed therebetween and the means by which the mattress sections are connected to such strip.

1 and 2 indicate portions of the end bars of a mattress frame. 3 and 4 indicate supplemental bars secured to the mattress frame and over which the ends of the mattress sections are stretched. 5 and 6 indicate the inner edge portions of two mattress sections.

45 In the drawing I have only shown two spiral strands 7 and 8 of each section, each formed of a plurality of wires which form the extreme inner edges of the mattress sections. The inner edges of the mattress sections are spaced apart as indicated. Interposed between these sections is located a band of spring metal 9 extending longitudinally of the mattress frame. 10 and 11 indicate a series of perforations located in each edge of the strip 9. 12 and 13 indicate two pair of spiral springs connecting the ends

of the strip 9 to the bars 3 and 4. The inner ends of the springs 12 and 13 are preferably passed through the end perforation of each series of perforations 10 and 11 in 60 order to connect the springs to the strip 9. The opposite ends of the springs 12 and 13 pass through perforations 14 formed in each of the bars 3 and 4.

15 and 16 indicate single spiral wires of 65 the same pitch as the spiral wires forming the mattress. The wires 15 and 16 are threaded through the inner edges of the multiple wires 8 forming the extreme inner edge of each mattress section. 17 and 18 70 indicate spiral wires also of the same pitch as the wires forming the mattress sections. The wires 17 and 18 are threaded through the perforations 10 and 11 as indicated. 19 and 20 indicate wires similar to the wires 17 75 and 18 which are threaded through the wires 17 and 18 as indicated, the inner edges of such spirals overlapping the opposing edges of the spirals 15 and 16, the spirals of the wires 19 and 20 being intermediate of the 80 spirals of the wires 15 and 16. 21 and 22 indicate stiff reinforcing wires. The wires 21 and 22 are passed longitudinally through the overlapping portions of the wires 19 and 15 on one side of the strip 9 and the wires 85 20 and 16 on the other side of the strip 9 thereby connecting the wires 19 and 15 and 20 and 16 together and consequently the inner edge of each mattress section 5 and 6 to the center strip 9. The ends of the wires 21 90 and 22 are passed through the spiral springs 12 and 13 at each end of the strip 9. The ends of the wires 17 and 19 are wound around the reinforcing wire 21. The ends of the wires 18 and 20 are wound around the 95 reinforcing wire 22. By this means a permanent connection is provided between the center strip 9 and the inner edges of the mattress section.

Although I have only described this invention in connection with the center strip it will, of course, be understood that a strip similar to the strip 9 may be provided at each mattress section outer edge to which the mattress section outer edge is similarly 105 connected.

When making up this mattress the sections 5 and 6 are first stretched upon the mattress frame thereby slightly increasing the pitch between the coils of the woven wire. The 110 distance between the perforations 10 and 11 is made to correspond to the pitch of the

woven wire of the mattress section after it is stretched and the spiral connecting wires connecting the inner edges of the mattress section to the center strip are also made to 5 correspond in pitch to the distance between the perforations so as to allow of an even stretch in the mattress from end to end when in use.

From this description it will be seen that 10 I have devised a very simple form of connecting means between the independent sections of a woven wire mattress and which will serve to support the longitudinal edges 15 of the mattress section so that they will not give and allow the mattress to sag either in the center or at the outer edges thereof so that when the mattress is in use the center of each section takes up the sag and therefore insures that they operate independ- 20 ently.

What I claim as my invention is—

1. In a woven wire mattress, the combination with the mattress frame and mattress section supported thereby, of a metal strip 25 extending longitudinally parallel with the mattress edge having a series of edge perforations, resilient means for connecting the ends of the strip to the mattress frame, a spiral wire woven through the edge perforations of the strip, and interengaging means between the spiral wire of the strip and the parallel edge wire of the mattress section.
2. In a woven wire mattress, the combination 35 with the mattress frame and mattress section, of a metal strip extending longitudinally and parallel with the edge of the mattress section and having a series of edge perforations, a woven wire portion engaging 40 with such edge perforations, a woven wire portion carried by the edge of the mattress section overlapping the woven wire portion extending from the strip, and a longitudinally extending reinforcing wire threaded 45 through such overlapping portions.
3. In a woven wire mattress, the combination with the mattress frame and mattress section, of a metal strip extending longitudi-

nally and parallel with the edge of the mattress section and having a series of edge 50 perforations, a woven wire portion engaging with such edge perforations, a woven wire portion carried by the edge of the mattress section overlapping the woven wire portion extending from the strip, a longitudinally 55 extending reinforcing wire threaded through such overlapping portions, and spiral springs connecting the ends of the strip to the mattress frame and through the convolutions of which the ends of the reinforcing wire extend.

4. In a woven wire mattress, the combination with the mattress frame and wire mattress section supported thereby, of a metal strip extending longitudinally parallel with 60 the edge of the mattress section and having a series of edge perforations, resilient means for connecting the ends of the strip to the mattress frame, a spiral wire threaded through the perforations of the strip, a spiral 65 wire threaded through the spiral wire passing through the perforations, a spiral wire threaded into the edge wire of the mattress, and overlapping the last mentioned spiral wire, and a reinforcing wire passing 70 through the overlapping spirals.

5. In a woven wire mattress, the combination with the mattress frame, of a mattress section stretched thereon, a longitudinal strip having edge perforations therein 80 spaced apart equal to the pitch of the spirals of the stretched mattress section, resilient means for connecting the ends of the strip to the mattress frame, woven wire spirals engaging the perforations of the strip, a woven wire spiral extending through the spiral of the edge wire of the mattress section, and interengaging means for connecting the spiral passing through the edge wire 85 of the mattress section and the spiral wires 90 passing through the perforations of the strip.

RUDOLPH COOPERSMITH.
